UNITED STATES PATENT OFFICE.

JOHN A. POTTER, OF PITTSBURG, PENNSYLVANIA.

COKE-OVEN AND GAS-PRODUCER.

SPECIFICATION forming part of Letters Patent No. 731,950, dated June 23, 1903.

Application filed June 24, 1902. Serial No. 112,958. (No model.)

To all whom it may concern:

Be it known that I, JOHN A. POTTER, of Pittsburgh, in the county of Allegheny and State of Pennsylvania, have invented a new and useful Improvement in Continuous Coke and Gas Producers, of which the following is a full, clear, and exact description, reference being had to the accompanying drawings, forming part of this specification, in which—

10 Figure 1 is a vertical transverse section through a double battery of gas and coke producers constructed in accordance with my invention. Fig. 2 is a partial vertical section at right angles to that of Fig. 1 through one 15 of the batteries, and Fig. 3 is a cross-section on the broken line III III of Fig. 1. Fig. 4 is a cross-section showing the shear-operating mechanism.

My invention relates to the manufacture 20 of gas and the coking of coal and is designed to provide an improved regenerative producer by which the gas formed may be taken off and partly used in aiding the coking operation, in which the coke is compacted and 25 made more dense, in which the operation is continuous, so that there is no alternate heating and cooling of the oven, in which the percentage of sulfur is reduced and the heat 30 of the cooling coke utilized to preheat gas and air.

In the drawings I show a double battery of 35 producers 2, built in parallel rows, with an open chamber 3 between the batteries. Each producer consists of a vertical stack having in the walls around its lower portion alternate air-flues 4 and gas-flues 5, which extend up and open into an annular checker-work chamber 6, which surrounds the middle and upper portions of the producer and is provided with staggered bricks 7, which baffle the flames and support the inner wall or retort. Gas is supplied to the lower end of the gas-flues by valved branches 8, leading from gas-supply pipes 9. The air-flues are 40 open at their lower ends to the outer air or may be connected to air-blast pipes. The flame and products of combustion passing from the chambers 6 enter a common flue 10, leading to a suitable stack, and the gases issuing from the upper part of the producers 45 pass through gas-offtake 11 to gas-mains 12,

leading to a suitable tank or reservoir. The coal is charged from a car 13, which travels lengthwise between the lines of two batteries, into the upper hoppers 14, which open into the tops of the producers. The lower ends 55 of these hoppers are closed by bells 15, which are made with solid heavy bottoms, as shown, and are secured at the lower ends to stiff vertical posts 16, having racks operated by pinions 17, which may be driven from a central main shaft 19. By thus arranging the bells they act not only as closures for the hoppers, but also as rams, by which the charge may be forced downwardly in case it 60 should cling to the walls in any part of the oven while a portion of coke is being discharged at the lower end.

The lower ends of the producer-chamber are closed by horizontally-moving shear-blocks 20, which rest and are reciprocated upon lower inclined guides 21, moving between these guides and castings 22, which form the base of the producer and contain water cooling-pipes 23, supplied by branches 70 24 from pipes 25. The shear-blocks are connected by rods 26 to cranks upon a shaft 27, having gear-wheels 27', intermeshing with pinions 35 upon a shaft 36, having a toothed wheel 37, intermeshing with a pinion 38 upon 75 an actuating-shaft 28. The inclined or wedge-shaped base-guide for the shear-blade acts to force it upwardly against the base-casting when the blade is moved to close the producer-bottom, thus sealing the opening. 80

To supply steam to the base of the charge in the producer, I employ flexible hose-pipes 29, leading from steam-pipes 30 to upwardly-directed nozzles 31 in the shear-blade casting. The coke emerging from the lower end of the 90 producer when the shear-blade is opened drops upon the base 32 and is sheared off and pushed out by the shear-blade when closing into coke-cars 33, traveling on tracks parallel with the batteries.

In the normal operation of the producers the charging-bell being lowered after a portion of coke is discharged from the lower end coal drops from the hopper upon the charge and gradually descends toward the 100 coking zone. The center of this coking zone is at about the point marked *a*, where obser-

vation-holes 34 are provided for examining the condition of the heat, &c., of the producer. As the coking goes on the gases produced in the coking operation pass up through 5 the coal in the upper part of the chamber and are drawn off into the gas-mains. The gas necessary for coking the coal is drawn from the gas-reservoir and passed in through the gas-pipes to the lower ends of the flues 5. 10 Air passes in at the base of the air-flues 4, and this air and the gas rise through the flues 4 and 5 and unite at the tops of the flues in the chamber 6 at about the level marked a. As the air and gas rise through the flues, 15 they are preheated by the heat radiating from the hot coke as it descends from the coking zone to the discharge-openings. This coke, which is at a temperature of about 3,000° at the coking zone, gives up its heat 20 to the side walls of the retort as it descends from this zone, which walls in turn give up their heat to the gas and air passing up to the combustion-chamber, so that when the coke reaches the discharge-opening it will 25 have then given up most of its heat. The heat of this coke descending from the coking zone is also utilized for generating hydrogen gas by introducing steam through the pipes 29. This steam coming in contact with the 30 hot coke is decomposed, the oxygen being consumed by the hydrocarbon contained in the coke, producing large quantities of hydrogen, which pass upwardly through the charge and associate with the gases distilled 35 from the coal, this being done at the expense of heat in the coke and while the coking process is going on in the upper part of the oven. These gases and steam at the same time remove from the coke any particles of 40 sulfur and hydrocarbon which may be left therein, thus improving its quality. 45 The preheated gas and air rising through the flues around the base of the chamber unite in the combustion-chamber and are ignited, burning within this chamber, so as to supply heat through the retort-walls to the charge in the coking zone, thus producing a coking operation. In the upper part of the chamber 6 the flame and gases indirectly 50 heat the fresh entering coal, and thus prepare it for the coking operation, the products passing from the top of this annular chamber to the stack. The coal at the upper part of the burden is thus heated from the hot walls, 55 which are of firebrick or refractory material, and this descending coal is brought into higher heats and gradually gasified and prepared for the final coking operation within the coking zone. 60 The shear-blade at the base of the producer is moved back from time to time as desired, thus allowing the charge to settle down, the coke discharging upon the base of the lower chamber. The shear-blade then being moved 65 back shears off the column, and fresh coal being introduced at the top the operation thus proceeds continuously. In starting the ap-

paratus one set of the connecting-rods 26 may be disconnected. If a lean coal is being used, by keeping a high burden within the producer the tar distilled during the coking will be deposited in the upper part of the burden, and thus enrich the coal. If this is not desired, the burden is kept low, and the tars will pass off with the gas. 75

The advantages of my invention will be obvious to those skilled in the art. By reason of the vertical stack arrangement of the producer or oven the weight of the charge will compact and densify the coke, thus greatly improving its utility and strength. The double-surface regenerative system utilizes the heat of the coke which has been produced in preheating the air and gases, which are then burned to carry out the coking operation. 80 Further, the heat and gases of the burning gas serve to preheat the upper portion of the charge and thus aid in the coking operation. The process being continuous, the walls are kept at a substantially uniform temperature, 85 so that the life of the producer is much longer than in the intermittent process, where the entire oven is discharged and the entire new charge put in. The coke being cooled down before discharging does not need to be water-quenched, and hence the splitting up of the coke from the sudden cooling is avoided and the depositing of the impurities in the water 90 in the coke is prevented. 95

The entrance of air to the oven is prevented 100 by the shear-blade, which acts as a seal, preventing the access of oxygen to the charge, this shear-blade cutting off the protruding lower portion of the charge as it is moved forward. By keeping the charge high a poor 105 coal can be enriched and made into a very desirable coking-coal, as the tars will be deposited in the coal passing down to the coking zone, and the gases passing up through the charge can be taken off. The heat of the 110 coke is also utilized for the formation of gas by introducing steam into the lower portion of the charge, this steam being broken up 115 and increasing and enriching the gas, as well as carrying off the injurious sulfur constituents of the coke. 115

The regenerative flues may be used for heating air only or combustible gases only or for heating both, as shown. The air or the combustible gases may be led through the side 120 to the upper ends of the regenerative flues, and by the word "gases" in the claims I mean to include air or combustible gas, and many other changes may be made in the form and arrangement of the producers, the regenerative system, the feed and discharge mechanisms, and the other parts of the apparatus without departing from my invention as defined in the claims. 125

I claim—

1. A coke and gas producer of stack form arranged to contain a vertical charge or burden, coal-feeding mechanism at the top thereof, mechanism at the bottom arranged to 130

- shear off and discharge a part of the charge, and a gas-offtake in its upper portion; substantially as described.
2. A coke and gas producer of vertical stack form arranged to contain a vertical charge, regenerative flues around its lower portion having gaseous inlets and arranged to heat said gases, a gas-offtake at the upper end of the producer and mechanism at the bottom of the producer arranged to shear off and discharge successive portions of the charge; substantially as described.
3. A coke and gas producer having regenerative flues for gases around its lower portion, mechanism at the bottom arranged to shear off and discharge successive portions of the column and a combustion-chamber around its intermediate portion having air-inlets and connected to said flues; substantially as described.
4. A coke and gas producer having regenerative flues around its lower portion arranged to heat the gases therein, means for supplying air and gas to the lower ends of the flues, and an annular combustion-chamber surrounding the middle and upper parts of the producer, and into which said flues open, said chamber having air-inlets; substantially as described.
5. A coke and gas producer having regenerative flues for gases around its lower portion, and a combustion-chamber containing baffle-bricks around its upper portions and connected to the flues, said chamber having air-inlets; substantially as described.
6. A coke and gas producer of vertical stack form having coal-charging mechanism at the top, coke-shearing mechanism at its lower end, and a pusher arranged to force the charge downwardly; substantially as described.
7. A vertical coke-oven having a movable shear-blade at its lower end; substantially as described.
8. A vertical coke-oven having a casting at its lower end, and a reciprocating shear-block movable between the casting and a lower guide; substantially as described.
9. A vertical coke-oven having a receiving-chamber below its lower end, and a movable shear-blade arranged to cut off the protruding portion and close the lower end of the oven; substantially as described.
10. A continuous coke-oven of vertical stack form, substantially closed to the outer air, mechanism for feeding coal into the top of the stack, mechanism for shearing off and removing a portion of the charge from the bottom of the stack, an inlet-pipe leading into the lower end of the stack, and a source of steam connected to said pipe; substantially as described.
11. A vertical stack coke-oven having a movable shear-blade at its lower end, and a pipe leading through the shear-blade and opening into the oven; substantially as described.
12. A coke and gas producer of vertical stack form, having regenerative flues around its lower portion, charging mechanism at its top, a gas-offtake leading from the upper part of the stack, and a movable shear-blade at the lower end of the stack; substantially as described.
13. A coke and gas producer of vertical stack form, having regenerative flues around its lower portion, a combustion-chamber around its upper portions into which the flues open, a gas-offtake from the upper end of the producer, a stack-flue leading from the upper end of the combustion-chamber, and a movable shear-blade at the lower end of the stack; substantially as described.
14. A coke and gas producer of vertical stack form, with mechanism for shearing off and discharging successive lower portions of the charge, and a gas-offtake at its upper end, regenerative flues around the lower portion of the stack and arranged to heat the gases contained in said flues, and a gas-supply channel connected to the regenerative flues at a point intermediate of the height of the stack; substantially as described.
15. A coke and gas producer, having mechanism at its lower end arranged to shear off and discharge successive portions of the charge, regenerative flues for gases around the lower portion of the producer, a combustion-chamber around its intermediate portion having air-inlets and connected to the regenerative flues, and a gaseous supply-channel connected to the regenerative flues; substantially as described.

In testimony whereof I have hereunto set my hand.

JOHN A. POTTER.
